United States Patent Office.

WILLIAM G. PERKINS, OF WALDEN, VERMONT.

Letters Patent No. 65,692, dated June 11, 1867.

IMPROVED ROLLING SCREEN FOR DOORS, WINDOWS, &c.

The Schedule referred to in these Letters Patent and making part of the same.

TO ALL WHOM IT MAY CONCERN:

Be it known that I, WILLIAM G. PERKINS, of Walden, in the county of Caledonia, in the State of Vermont, have invented a new and improved Winding Screen, which may be used for doors, shutters, &c.; and I do hereby declare that the following, taken in connection with the drawings which accompany and form part of this specification, is a description of my invention sufficient to enable those skilled in the art to practise it.

This invention relates to that class of winding screens which are made up of strips or slats of metal or wood, and which are so united and arranged as to be capable of being wound upon a spindle or drum. As it is the principal design of this invention to produce a screen to serve as a door for barns, and for similar use, though it is otherwise applicable, it was a desideratum to make the construction in a simple, inartificial manner, so as to have special reference to the nature of wood, in which, rather than in metal, I propose mostly to embody my invention. And as I propose to make use of cords or straps as suspensors, in connection with strips or slats, my invention has reference to provision for automatically keeping the edges of the strips or slats in close contact, under any changes of the length of the suspensors, and under any changes of the width of the slats caused by swelling or shrinking.

My invention consists in so forming the slats that of two adjoining edges of any two slats, one shall be concave and the other correspondingly convex, so that the one fits into the other, but is left free to move as may be necessary in winding, without disclosing a crack or opening between the slats, and in suspending slats so formed upon ropes, wire, cords, straps, chains, &c., in such manner as to be free to slide or move upon the suspensors, as well as to move with them, the lower slat alone being fixed so as to have no movement relative to the length of the suspensors.

The drawing shows an embodiment of my invention, the view being a vertical section, taken through one of the suspensors, the slats and shaft, or windlass, and showing the frame or casing in elevation beyond.

a is one of the suspensors, *b* the slats or strips, *c* the windlass, which has attached to it, by other suitable suspensors, weights for counterbalancing the weight of the entire screen. The weights and their suspensors, and means of attachment, are not shown in the drawing, as they are similar to other appliances well known; the weights may be concealed or boxed up in the casing if desired. The slats are bored so that they can be moved freely on the suspensors, and the lower slat being fixed on the suspensors, it is evident that the edges of all the slats will be kept in contact with the adjacent edges, by the mere weight of the slats, and without any adjustment or manipulation whatever. While in the drawing one edge of each slat is shown as convex, and the other edge as concave, both edges of one slat may be concave, if both edges of the next slat are convex. To effectually prevent the screen from displacement, the ends of the slats move in grooves in the frame, the width of the grooves being made to correspond to the thickness of the slats.

I claim the winding screen made up of slats, with edges, as described, when arranged on suspensors as specified.

WILLIAM G. PERKINS.
